UNITED STATES PATENT OFFICE.

WALTER Z. SCHULTE, OF MADISON, WISCONSIN, ASSIGNOR TO BURGESS BATTERY COMPANY, A CORPORATION OF WISCONSIN.

DRY CELL AND METHOD OF MANUFACTURING THE SAME.

1,370,054.

Specification of Letters Patent.

Patented Mar. 1, 1921.

Application filed May 15, 1920. Serial No. 381,652.

To all whom it may concern:

Be it known that I, WALTER B. SCHULTE, a citizen of the United States, residing at Madison, in the county of Dane, State of Wisconsin, have invented certain new and useful Improvements in Dry Cells and Methods of Manufacturing the Same; and I do hereby declare the following to be a full, clear, and exact description of the invention, such as will enable others skilled in the art to which it appertains to make and use the same.

The present invention relates to dry-cells of the "bag" type, and particularly to the cathodes of such cells and to the method by which the cathodes are provided with a wrapping of bibulous material to prevent the electrode from disintegrating into the surrounding gelatinous electrolyte, but nevertheless allowing the free flow of current to the electrode from the electrolyte.

The objects and advantages of the present invention will be made clear by the following detailed description, which is to be taken in conjunction with the accompanying drawings, wherein—

Figure 1 is a perspective view of a dry cell cathode constructed in accordance with the present invention; and Fig. 2 is a sectional elevation through a complete dry-cell.

In the manufacture of dry-cells of the "bag" type, it is customary to prepare a mixture or "mix" of manganese dioxide, such as pyrolusite, carbonaceous material, such as graphite, or a mixture of graphite and retort carbon, and usual salts and water, as explained, for instance, in Burgess United States Patent No. 1,162,449, dated November 30, 1915, and then to compress this damp and plastic mixture about a carbon rod to form a "core" or cathode for the dry-cell. This molding of the plastic mix into cylindrical form with a carbon rod in the center may be done in suitable apparatus, as, for instance, in the tamping machine of Hamblechen United States Patent No. 1,232,297, dated July 3, 1917. The cathodes so formed, although strong enough for manipulation on a factory basis, are nevertheless fragile in character and subject to disintegration, particularly if their moisture content is changed substantially from that at which they are molded.

A customary way of protecting such a

molded cathode from disintegration during the further steps in the assembly of a complete dry-cell is to wrap the core with cheese-cloth. The cheese-cloth is a fine grade, un-sized material, and in conformity with usual practice, is held in place around the core with a wrapping of thread. The cloth is brought around the bottom of the core and over the top, and the thread is wound not only around the perimeter of the core but also longitudinally and parallel with the carbon pencil. The wrapped core so produced can then with advantage be dipped into a very shallow layer of melted paraffin to form an insulating layer or film across the bottom, as explained, for instance, in Burgess United States Patent No. 1,211,363, issued January 2, 1917. The cheese-cloth is expensive and the operation of winding the wrapped cores with thread, being a hand operation, is tedious and likewise expensive. Also, there is danger that through unskilled handling the soft and plastic cores will be deformed. Also, some of the active mix may find its way to the outside of the cheese-cloth wrapping and on assembly of the dry-cell be washed over into contact with the zinc, where it can produce local action with destructive results.

In conformity with the method of the present invention, the bibulous envelop or wrapping for the cathode is held in place, not by winding with thread, but by means of an adhesive. This method permits the use of paper in place of cheese-cloth as the bibulous material and there is much economy not only in materials but also in labor. Likewise there is some gain in the quality of the dry-cell, as hereinafter explained.

The papers that are most suitable for wrapping cores are good quality, thin and porous tissue papers. A slightly calendered surface is not objectionable. The adhesive which I find most suitable is one that is thin but does not settle. A starch, such as arrow-root, when made up in the proportions by weight of about one per cent. arrowroot in boiling water is very satisfactory. The adhesive should have a sizing property—that is to say, should fill the pores of the paper rather than soak through it.

The preferred mode of wrapping cores with paper is to have the paper cut to proper size so that an operator can easily pick up

one sheet at a time. The adhesive is applied to the sheet as by smearing it on with a brush or a gluing machine or roller. The paper takes up a film of adhesive quickly and is then placed on the core and wrapped around. The operator squeezes out any air pockets which would otherwise impair the battery, and then turns over the upper and lower edges of the wrapping to cover the top and bottom of the core. Preferably the paper is cut so that the grain is parallel to the axis of the electrode when the wrapping is in place, for this reduces the danger of its tearing at the corners when it is folded over at the top and bottom of the core.

The construction above described is illustrated in Fig. 1, where 1 is the carbon rod with its brass cap 2, and where the molded mix 3 is wrapped about with a sheet of paper 4, a fragment of which, in the drawing, is illustrated as torn and folded down at 5 to diagrammatically illustrate the character of the wrapping.

The cores can now be set aside and are soon dry enough for subsequent operations. The bottom of the core may be given a film 6 of paraffin by dipping the core into a thin layer of melted paraffin, and the core can then be lowered into a zinc cup, as in usual practice, and a suitable gelatinizable paste be introduced between the zinc cup and the cathode.

Fig. 2 of the drawing shows a core properly installed in its zinc container 7 with a layer of gelatinized paste intervening. This paste may consist of a mixture of zinc chlorid, ammonium chlorid and a suitable cereal, such as cornstarch and water, and may be so constituted as to set or gelatinize in a few minutes without the need for steaming or cooking, as explained, for instance, in Hambuechen Patent No. 1,292,764, dated January 28, 1919. The cell can then be finished off with a paraffin washer 8 and a seal 9 of pitch or sealing wax, all in conformity with usual practice.

The salts from the electrolyte quickly penetrate into and through the layer of starch adhesive, ultimately establishing equilibrium between the gelatinous electrolyte and the core, as is well understood. The zinc chlorid of the mix and of the electrolyte attacks the wood fiber of the bibulous envelop, converting the paper in part, at least, into a rubbery or parchmentized mass through which salts and moisture readily diffuse. This assures a path of low resistance from the anode to the cathode, and gives to the finished cell desirable electrical characteristics, as will be well understood. This progressive disintegration of the paper envelop is not a disadvantage, for after complete gelatinization of the electrolyte, the need for a bibulous envelop on the core disappears, and the ease with which the elec-

tricity can flow from the zinc to the carbonaceous cathode becomes of prime importance.

There is advantage in the present method because of its cheapness, both in labor and in material. It is possible to use a thin paper, thereby economizing in space as well as insuring the good electrical characteristics above mentioned. The mechanical operations of wrapping the core are easy. The paper only is picked up and smeared with the adhesive, and this is easier than picking up the core and dipping it into a bath of adhesive preparatory to applying the paper. There is no need for separating the cores after they have been wrapped, and while they are drying in the trays, as the adhesive does not come through the paper to any considerable extent, and the cores do not attach themselves to one another. There is one precaution that can advantageously be kept in mind. The core softens some as the result of the application to it of the sheet of paper with its moist layer of adhesive, and the moisture may soak through the core to the carbon rod, thereby loosening the rod in the surrounding block of compressed mix. This condition is but temporary, for as soon as the adhesive sets, the tendency toward looseness disappears. If, therefore, the cores be not roughly handled during the short interval after wrapping, and before setting of the adhesive, no manufacturing trouble is experienced.

Bibulous material other than paper, and an adhesive other than starch, may be employed, and various changes in the method of their use may be made, without departing from the spirit of the invention as defined by the appended claims.

In my application, Serial No. 381,653, filed concurrently herewith, I have described and claimed the method which consists in impregnating the cathode with an adhesive and then wrapping said cathode with a bibulous envelop which is secured in place by said adhesive.

I claim:—

1. A dry cell cathode of the bag type having a bibulous envelop pasted in place; substantially as described.
2. A dry cell cathode of the bag type having a paper envelop pasted to the top, bottom and sides of the depolarizing mix.
3. A dry cell cathode of the bag type having a paper envelop pasted in place with a starch adhesive; substantially as described.
4. A dry cell cathode of the bag type having a layer of tissue paper completely enveloping the depolarizing mix and pasted thereto, to prevent disintegration of the mix into the surrounding gelatinized electrolyte; substantially as described.
5. A dry cell having a fragile molded cathode, a bibulous envelop pasted to said cathode, a

cathode, and a gelatinized electrolyte surrounding said envelop; substantially as described.

6. In the manufacture of a dry cell of the bag type, the step which consists in pasting the bibulous envelop to the cathode preparatory to addition of the electrolyte; substantially as described.

7. In the manufacture of a dry cell of the bag type, the step which consists in pasting a paper envelop to the cathode preparatory to addition of the electrolyte; substantially as described.

8. In the manufacture of a dry cell, the steps which consist in smearing a fiber sheet with adhesive and then wrapping and folding said sheet about the cathode mix to serve as a bibulous envelop separating the mix from the surrounding gelatinized electrolyte; substantially as described.

9. In the manufacture of a dry cell, the

steps which consist in smearing a paper sheet with starch adhesive and then wrapping and folding said sheet about the cathode mix to serve as a bibulous envelop separating the mix from the surrounding gelatinized electrolyte; substantially as described.

10. In the manufacture of a dry cell of the bag type, the steps which consist in molding a depolarizing mix about a carbonaceous rod to form a fragile cathode, smearing a sheet of tissue paper with starch adhesive, wrapping and folding said sheet about the top, bottom and sides of the cathode mix to serve as a bibulous envelop, and introducing the enveloped cathode and a gelatinizable paste into a zinc cup serviceable as anode for said cathode; substantially as described.

In testimony whereof I affix my signature.

WALTER B. SCHULTE.
